WASHING MACHINE

Roman B. Bukolt, Stevens Point, Wis.

Application November 7, 1939, Serial No. 303,264

9 Claims. (Cl. 68—151)

The invention relates to improvements in washing machines of the general type in which an agitator is mounted for oscillation on a vertical axis within a tub having a bowl-like bottom, and it aims to provide a new and improved agitator which will centrifugally move the wash water in such manner as to effectively circulate the same and cause repeated passage thereof through the articles being washed, at the same time, gently pressing the articles against and moving them upon rubbing surfaces of the agitator, thereby effectively loosening all dirt and thoroughly rinsing same from the fabric.

With the foregoing and minor objects in view, the invention resides in the novel subject matter hereinafter described and claimed, description being accomplished by reference to the accompanying drawings.

Figure 1 is a vertical sectional view showing the improved agitator incorporated in a washing machine.

Figure 2 is a top plan view of the agitator, partly broken away and in horizontal section.

Figure 3 is a detail section on line 3—3 of Fig. 2.

Figures 4 and 5 are respectively, a partial section and a top plan showing a modification.

Figures 6 and 7 are views similar to Figs. 4 and 5 showing a further variation.

Reference is first made to the form of construction shown in Figures 1 to 3.

The improved agitator A is shown centrally mounted within a tub T having a bowl-like bottom B, the peripheral portion of which curves upwardly at C to the side wall W. The agitator A, however, could be used to good advantage in a tub having a more or less inverted conical bottom. I have shown a tubular post P secured to the bottom B and extending upwardly therefrom, said post having internal bearings P' and B' for a vertical shaft S to be oscillated by any conventional mechanism (not shown), a portion of the mechanism, however, being illustrated at M. The upper end of the shaft S has a splined or other detachable connection D with a sleeve 5 forming part of the agitator A, the upper end of said sleeve being closed at 6. The lower end of the sleeve 5 has a tight-pressed connection with the hub 8 of the agitator, or said sleeve 5 is otherwise suitably secured to said hub. When a pressed connection is employed, it is preferably splined and it may be additionally riveted as indicated at 7'. The hub 8 is preferably provided with an internal bearing collar 10' which rotat-

ably surrounds the lower portion of the tubular post P.

The hub 8 is preferably of the substantially conical form shown, and a plurality of circumferentially spaced spokes 9 radiate from the lower portion of said hub, said spokes having flat vertical sides 10. The lower edges of these spokes are near the bottom B of the tub T, and the outer end portions of said spokes preferably turn upwardly to some extent as shown at 9'. Alternate upper and lower segmental plates 11 and 12 extend between the spokes 9 and are integrally or otherwise rigidly secured to the upper and lower edge portions of said spokes and to the hub 8. The outer ends of the upper plates 11 are turned upwardly to some extent as shown at 11' and the same is true of the outer ends 12' of the plates 12. The plates 11 and their upwardly turned ends 11' are formed with perforations 13, the upper ends of which are countersunk, providing said plates with gentle rubbing surfaces for contact with the articles being washed and at the same time making provision to allow downward passage of water through the plates. The upturned ends 12' of the plates 12 are provided with perforations 14 which are preferably identical with the perforations 13, but the major portions of said plates 12 are imperforate in the preferred construction. While mentioning the portions 12', attention is invited to the fact that the outer ends 9' of the spokes 9 project outwardly beyond said portions 12' and form paddles for radially moving the wash water.

The various plates 11 and 12 and the spokes 9 coact in forming alternate upwardly open pockets 15 and downwardly open pockets 16, all of said pockets having substantially flat vertical sides formed by the sides 10 of said spokes. The outer ends of the pockets 16 are open but the outer ends 12' of the plates 12 constitute perforated end walls for the pockets 15.

When the agitator A is oscillated within the tub filled with water, the spokes 9 centrifugally move the water, causing it to flow outwardly and upwardly along the wall W of the tub and downwardly over the central portion of the agitator, as indicated by the arrows. The upward and outward inclinations of the pocket end walls 12' and the ends 11' of the upper plates 11, assist in upwardly directing the water. As the water is displaced from the downwardly open pockets 16 due to centrifugal action, more water must enter these pockets, with the result that this water passes downwardly through the perforations 13 and in so doing passes through the articles being

washed, at the same time, gently rubbing them against the perforated rubbing surfaces of the plates 11. As the water in the pockets 15 is moved centrifugally, some of it passes through the perforations 14 of the end walls 12' and in so doing, passes through some of the fabric and presses it against the rubbing surfaces of said end walls. The articles being washed, of course, move with the water in the directions indicated by the arrows in Fig. 1 and at the same time, are oscillated with the movement of the agitator A. Thus, in a short while, all surfaces of the articles will come in contact with the rubbing surfaces of the agitator and the washing liquid will be forced to travel a number of times through the fabric. All dirt is thus effectively loosened and thoroughly rinsed out. As the clothes descend around the sleeve 5, the conical hub 8 overcomes any tendency which they may have to collect at the center of the agitator, insuring that they shall move outwardly with the currents of water centrifugally induced by the agitator oscillation. In the present disclosure, the opposed side walls of the pockets 15 and 16 and the outer ends 9' of the spokes 9 are all instrumental in centrifugally moving the water as the agitator is operated. The bowl-like bottom of the tub T is of course responsible to some extent for the directional movements of the water and the clothes, but these movements are also caused to quite an extent by the upward and outward inclinations 11' and 12' at the outer ends of the plates 11 and 12, respectively.

While, in all forms of the invention, the agitator is of bowl-shape, this shape is accentuated in the agitator A' shown in Figs. 4 and 5 and in the very similar agitator A² illustrated in Figs. 6 and 7. The two agitators A' and A² are so similar that one description will apply to both, coupled with an explanation as to the difference. The central portion 20 of the agitator is substantially imperforate, although it is provided with a number of small openings 21 to permit draining of water therefrom when draining the tub, said portion 20 being suitably secured to a central hub 22 which may well be of the conical form shown. Suitably secured to and projecting upwardly from the hub 22 is a tube or sleeve 23 which may be mounted and oscillated in the same manner as the tube or sleeve 5, above described.

Alternate steeply inclined plates 24 and less steeply inclined plates 25 are secured to the central portion 20 and incline outwardly and upwardly therefrom, all of these plates being provided with countersunk perforations 26. Vertical triangular walls 27 extend from the substantially radial edges of the plates 24 to the corresponding edges of the plates 25 and cooperate with the central portion 20 and the plates 24 in forming radially disposed pockets 28 which will centrifugally move the wash water and clothes as the agitator is oscillated. Centrifugal movement is also imparted to the wash water by radially disposed paddles 29 which project beyond the plates 24 and 25 in line with the walls or plates 27.

The agitator A' shown in Figs. 4 and 5 is intended for use in a bowl-like tub T', the shape of which cooperates with the shape of the agitator in causing movement of the clothes and wash water as indicated by the arrows.

The form of construction illustrated in Figs. 6 and 7 may well be used with a flat bottomed tub T² and to assist in directing the water upwardly

as it discharges from the pockets 28 and in fact as it leaves the entire periphery of the agitator, an upwardly curved rim 30 is provided under the perforated plates 24 and 25, being secured to the paddles 29 and to the central agitator portion 20.

The improved agitator operates on what I term a lateral flow vacuum and inertia pressure principle, the advantages of which are that it provides more room in the tub for a larger amount of clothes; forces the flow of water through the fabric by the inertia pressure of water and vacuum; rubs the fabric over a perforated wall or barrier of the rubbing bowl or agitator to loosen the dirt while the water flows through the fabric; provides a strong yet harmless washing action; and will wash clothes cleaner in a relatively short time, without injury.

When the tub is filled with water and clothes and the agitator or rubbing bowl is set into oscillating motion, the water will be expelled centrifugally or in lateral directions, causing the water to flow through the perforations in the agitator or bowl, from the inside to the outside, which flow is converted to an upward movement as shown by arrows in a number of the views. The water which returns to the bottom of the tub, at the central portion of the latter, causes the clothes to flow toward the outer inclined perforated wall or rim portion of the agitator. When the clothes reach this perforated wall or rim portion, the free flow of water through the perforations is stopped by the clothes and thus more or less of a vacuum is created on the other side, which will press the clothes against the inside surface by atmospheric pressure. Due to the buoyancy and the weight of the clothes and water, the clothes are not set into motion immediately upon starting of the agitator or rubbing bowl in either direction and thereby will be gently rubbed against the perforated rubbing surfaces of said agitator or rubbing bowl. As the clothes accelerate with the movement of the agitator or bowl, a centrifugal force or pressure is additionally applied to the clothes, pressing them still more firmly against the perforated portions of the agitator or bowl while the water is passing through them. The clothes are forced to move outwardly and upwardly over the perforated inclined wall or rim portion of the agitator or bowl and are circulated with the water which returns to the bottom of the tub, at the center of the latter.

Further examples of the generic invention herein claimed are found in my copending U. S. application Serial No. 303,263, filed November 7, 1939.

I claim:

1. A washing machine agitator comprising a central hub to be mounted on a vertical axis, an even number of substantially horizontal circumferentially spaced spokes radiating from said hub and having substantially vertical sides, alternate upper and lower substantially horizontal segmental plates extending between and secured to said spokes, the outer ends of said upper and lower plates being upwardly extended, said upper plates being perforated, said upwardly extended ends of said lower plates being perforated and the major portions of said lower plates being substantially imperforate; said spokes and said upper and lower plates forming a disk having alternate upwardly open and downwardly open pockets which centrifugally move the wash water when the agitator is turned

upon said vertical axis, causing downward flow of water through the perforations of said upper plates and outward flow of water through the perforations of said upwardly extended ends of said lower plates.

2. A structure as specified in claim 1; said perforated outer ends of said lower plates being inclined upwardly and outwardly to upwardly direct some of the wash water.

3. A structure as specified in claim 1; said spokes having outer ends projecting beyond said perforated upwardly extended outer ends of said lower plates and constituting blades for centrifugally moving the wash water.

4. A washing machine agitator comprising a substantially horizontal disk-like central portion having means for mounting it on a vertical axis, alternate steeply inclined and less steeply inclined perforated plates inclined outwardly from said disk-like central portion, and vertical radially disposed walls extending from the edges of the steeply inclined plates to the edges of the less steeply inclined plates.

5. A structure as specified in claim 4; together with radially disposed paddles projecting outwardly beyond said perforated plates in line with said vertical walls.

6. A structure as specified in claim 4; together with an outwardly and upwardly directed continuous rim underlying said perforated plates and joined to said central disk-like portion, and vertical paddles extending between said rim and said perforated plates in line with said vertical walls.

7. In a clothes washing machine, a tub member to contain wash water and clothes, a shallow bowl-like disk member in said tub member and mounted for oscillation on a vertical axis, said disk member having an outwardly inclined pe-

ripheral portion for upwardly directing the wash water and clothes when they are moved radially, said inclined peripheral portion having perforations through which some of the radially moved water may flow, and horizontally elongated paddles fixedly secured to and projecting downwardly from said inclined perforated peripheral portion and extending radially substantially throughout the width thereof, whereby said paddles will centrifugally displace the wash water under said inclined peripheral portion and thus cause the water within the confines of said inclined peripheral portion to flow through said perforations and press the clothes against said inclined peripheral portion while said portion is directing water and clothes upwardly.

8. A structure as specified in claim 7; one of said members being provided with an additional and continuous outwardly inclined portion under said paddles and secured to the lower edges thereof for upwardly directing the water which is centrifugally moved by said paddles.

9. A structure as specified in claim 7; said disk member having circumferentially spaced substantially segmental relatively low flat portions, other substantially segmental relatively high flat portions between said relatively low flat portions, and vertical radially disposed walls joining the radial edges of said high portions with those of said low portions, both said high and low portions extending outwardly to the aforesaid inclined perforated peripheral portion of said disk member, said relatively high and low portions and said radially disposed walls providing said disk member with downwardly open pockets open at their outer ends, and with upwardly open pockets having said inclined perforated peripheral portion across their outer ends.

ROMAN B. BUKOLT.
